CLAIM

The ornamental design for an overcap, as shown and described.

DESCRIPTION

FIG. 1 is an isometric view of a top, front, and right side of an overcap;

FIG. 2 is a front elevational view of the overcap of FIG. 1, the rear, right, and left sides being identical thereto; and, FIG. 3 is a top plan view of the overcap of FIG. 1.

The broken lines are included for the purpose of illustrating portions that form no part of the claimed design.
